UNITED STATES PATENT OFFICE.

LEOPOLD JANISCH, OF BERLIN, GERMANY, ASSIGNOR TO GENERAL ELECTRIC COMPANY,
A CORPORATION OF NEW YORK.

MOTOR-CONTROLLING DEVICE.

No. 926,874.

Specification of Letters Patent.

Patented July 6, 1909.

Application filed October 10, 1907. Serial No. 396,700.

To all whom it may concern:

Be it known that I, LEOPOLD JANISCH, a subject of the Emperor of Germany, residing at Berlin, Germany, have invented certain new and useful Improvements in Motor-Controlling Devices, of which the following is a specification.

This invention relates to the controlling of electric motors and has for its object the provision of means whereby an electric motor may be started, stopped, and generally controlled in a reliable and efficient manner.

My invention relates more specifically to the starting of electric motors which must be operated under various conditions of load and speed. In the starting of motors working under widely varying load, difficulties have arisen by reason of the fact that the same starter must serve for the starting of the motor both at full load and low speed and at no load and low speed. It is, for example, necessary in hoisting apparatus to so design the starting or controlling device that the operation is always slow in the first controller position. This is attained by causing the resistance connected in series with the armature to choke a large portion of the potential of the system. In hoisting apparatus if the series resistance is so proportioned that a half load is raised at the first position of the controller with a comparatively low speed then a full load may be given a downward instead of an upward movement as the current may be insufficient not only to lift the load but even to hold it at all. The result may be that upon the next movement of the controller a shock is caused since the lifting mechanism passes suddenly from the falling to the lifting movement without pausing at the position of rest. It has been sought to overcome these difficulties by means of mechanical brakes, and the like, which are operated manually but as such devices are inconvenient and absorb a great deal of power in the form of motor current they are generally unsatisfactory.

In the accompanying drawings Figures 1 to 4 show various modifications of my invention and Fig. 5 shows the drum controller employed in connection therewith.

Referring first to Fig. 1 it will be seen that I have provided in connection with the ordinary starting resistance, divided into sections and a controller for successively cutting out such sections, an electro-magnetic switch ar-

ranged to cut out one of the sections upon the first controller contact, that is, as soon as the motor circuit is closed. If the motor is running with no load or a light load, this position will give the motor sufficient speed but if the safe speed is exceeded the section of resistance is again automatically thrown into circuit. In this figure, A is the armature and F the series field of the motor.

The resistance R' is divided into sections by means of contact studs 10, 11, 12, 13 and 14 adapted to be engaged by the segments 10', 11', 12', 13' and 14' on the drum controller. There is also a stud 15 at the top of the controller engaged by the segment 15' and a similar stud 16 at the bottom of the controller engaged by the segment 16', the two studs 15 and 16 being electrically connected as shown. The first section R' of the resistance to be cut out is arranged to be short circuited by means of a solenoid switch having a movable contact 17 adapted to bridge the contacts 18 and 19 when the coil 20 is energized so as to draw up its core 21. This core also has attached to it a contact 22 adapted when the coil 20 is energized to bridge contacts 23 to complete the circuit of coil 24 in shunt to the motor armature A. This coil 24 when it is energized operates the contact 25 to bridge the contacts 26 and 27 short circuit the coil 20. A resistance 27 is arranged so that a part of it is connected in series with the coil 20, when the latter operates its contactor, by means of a contact finger 28 which engages the wing contact 29 on the controller in the initial position. When contact is made at this finger a part only of the resistance 27 is connected in series with the coil 20 so that the latter will be sufficiently energized to operate its switch 26 but after the finger springs pass the wing contact the whole of resistance 27 is connected in series with the coil so that, while enough current passes to hold the switch closed, it cannot be closed again without moving the controller backward to the initial position.

The mode of operation of the device shown in Fig. 1 is as follows: When the controller is moved to the first position 1, contact is made between the contact finger 28 and the wing contact 29 and between the stud 15 and contact segment 15'. In this position contact is also made between the studs 10 and 16 and their corresponding

contact segments 10' and 16'. With the controller in this position current passes from the main at L to conductor 30 through coil 20, conductor 31, part of resistance 27, conductor 32, finger 28, contact 29, segment 15' and conductor 32, back to line at L'. Solenoid 20 being energized with only a part of resistance 27 in series will raise its core and bridge contacts 18 and 19 which will short circuit section R' of the resistance. Current through the motor will then pass from line at L through the armature A, series field F, resistance R, conductor 33, contacts 18, 17 and 19, conductor 34 to stud 10 and contact segment 10', thence across to segment 16' and stud 16 back to line at L'. If the load on the motor is light, the armature will speed up, due to the cutting out of the section R'. If, however, the speed exceeds a predetermined safe value the coil 24, which is connected across the armature terminals will be sufficiently energized to raise its contact 25 to bridge the contacts 26 which will short circuit the coil 20. The result will be that the core 21 and contact 17 will drop, the contact 17' taking the arc, and the resistance R' will be thrown in series with the motor. This section R' of resistance is so calculated that it will not permit the armature to rise above a safe speed. In this first position of the controller the finger 28 has snapped off the wing contact 29 so that the contactor 17 will not be again raised. If there is a load on the motor the next movement of the controller in the position 2 will short circuit the section R' through the segments 10' and 11'. It will be seen that the section R' of resistance is first short circuited by means of the switch and then through the controller contacts and by continuing the movement of the controller the remaining sections of the resistance R will be short circuited in the usual way. By this arrangement it will be seen that the motor may be started with no load at a safe speed and also be operated on the first contact with a heavy load.

In the form shown in Fig. 2 special series resistance R² is connected in series with the resistance R. In this form when the coil 20 is energized upon the first controller position the resistance R² is short circuited and, as in the case of Fig. 1, the short circuit is opened by the energizing of the coil 24 when the safe speed is exceeded. When the short circuit is opened the resistance R² is connected in series with the resistance R and after all of the resistance R is cut out the resistance R² will still be in circuit so as to prevent the normal speed from being exceeded. Otherwise the form of device shown in Fig. 2 operates in the same manner as that shown in Fig. 1.

In Fig. 3 I have shown an arrangement for starting motors which it is desired shall start with a very low speed and after a certain

speed is reached the speed will then be increased. Motors operated for lifting grain sacks and the like must often be started in this way since if the movement at starting is too violent the sacks will be torn, while if the movement is brought about gradually the increase in the speed is unobjectionable. In this case a resistance R³ is connected in parallel with the motor armature A, when the controller is moved to the first position, by means of the contactor 17, and this resistance acts as a brake and reduces the speed of the motor. When, however, the speed reaches a predetermined point the coil 20 will be short-circuited by closing of contacts 25 26, due to the energizing of the coil 24, and the circuit of the resistance R³ will be opened. This will speed up the motor since by this time the inertia of the load has been overcome and the speed of the motor may be increased without danger to the load. The method of operation of the arrangement of Fig. 3 is otherwise the same as that of the arrangements shown in Figs. 1 and 2.

In Fig. 4 is shown a combination of the arrangements shown in Figs. 1 and 3. This arrangement is designed to produce a large decrease of the motor speed at mean and full load. Parallel brake resistance R³ is employed in addition to the resistance R' in series with the starting resistance R. When the solenoid 20 is energized on the first controller position the resistance R³ will be connected in parallel with the armature A and at the same time the resistance section R' will be short-circuited. In this way with a full load the speed of the armature will be greatly reduced because of the parallel resistance R³, while if the load is light it will not have this effect and the motor can be run at comparatively high speed or the speed may be limited as described with reference to the device shown in Figs. 1 and 3.

It will be seen that I have provided a very convenient and efficient arrangement for starting motors under varying conditions of load and running both at a high and a low speed.

Various modifications of my invention will, of course, suggest themselves to those skilled in the art without departing from the spirit of my invention, the scope of which is set forth in the annexed claims.

What I claim as new and desire to secure by Letters Patent of the United States, is:—

1. In combination an electric motor, a controlling mechanism therefor, a resistance, a switch for controlling the relation of said resistance to the motor circuit, means co-operating with said controlling mechanism for closing said switch in the initial movement of said controlling mechanism, and means responsive to the speed of said motor for opening said switch.
2. In combination an electric motor, a con-

- troller therefor, a resistance, a switch for controlling the relation of said resistance to the motor circuit, means coöperating with said controller operative only in an initial position 5 thereof for closing said switch, and means responsive to the speed of said motor for opening said switch.
3. The combination with an electric motor and controlling mechanism therefor, of a resistance in the motor circuit, an electro-magnetic switch arranged to throw said resistance in and out of the circuit to vary the motor speed, and connections whereby said switch is operated to affect the circuit upon 10 the initial movement of the controlling mechanism and restored when the motor reaches a predetermined speed.
4. The combination with an electric motor and controlling mechanism therefor, of a resistance in the motor circuit, an electro-magnetic switch arranged to throw said resistance in and out of circuit to vary the motor speed, and means whereby said switch is closed by the initial movement of the controlling mechanism and opened when the motor reaches a predetermined speed.
5. The combination with an electric motor, of means for starting the same comprising a resistance, controlling mechanism 30 therefor, an electro-magnetic device arranged to remove a portion of the said resistance from the motor circuit upon the initial movement of the controlling mechanism, and means for restoring the said portion of resistance 35 when the motor reaches a predetermined speed.
6. The combination with an electric motor and controlling mechanism therefor, of a switch arranged to vary the motor speed, and means whereby said switch is moved in one direction to increase the motor speed upon the initial movement of the controlling mechanism and is moved in the other direction to decrease the motor speed when the 40 motor reaches a predetermined speed.
7. The combination with an electric motor, of means for starting the same comprising a resistance, controlling mechanism therefor, a switch arranged to remove a portion 50 of the said resistance from the motor circuit upon the initial movement of the con-
- trolling mechanism, and means for restoring the said portion of resistance when the motor reaches a predetermined speed.
8. The combination with an electric motor 55 and controlling mechanism therefor, of an electro-magnetic switch arranged to vary the motor speed, means whereby said switch is closed by the initial movement of the controlling mechanism and opened when the 60 motor reaches a predetermined speed, and connections whereby said switch will not again close until the controlling mechanism is moved to the initial position.
9. The combination with an electric motor 65 and controlling mechanism therefor, of an electro-magnetic switch arranged to vary the motor speed, connections whereby said switch is energized by the initial movement of the controlling mechanism, and an electrically controlled device arranged to deenergize 70 said switch when the motor reaches a predetermined speed.
10. The combination with an electric motor, of means for starting the same comprising 75 a series of resistances, controlling mechanism for successively short circuiting said resistance, an electro-magnetic switch arranged to short circuit a portion of said resistance before it is short circuited by the 80 controlling mechanism, and means for opening said short circuit when the motor reaches a predetermined speed.
11. The combination of an electric motor, of means for starting the same comprising a 85 series of resistances, controlling mechanism for successively short circuiting said resistances, an electro-magnetic switch, connections whereby said switch is energized to short circuit a portion of said resistance upon 90 the initial movement of the controlling mechanism and before it is short circuited by said mechanism, and means for opening said short circuit when the motor reaches a predetermined speed.

In witness whereof, I have hereunto set my hand this twenty-fourth day of September, 1907.

LEOPOLD JANISCH.
